UNITED STATES PATENT OFFICE.

JOSEPH P. HULL, OF EASTON, DELAWARE.

FASTENER FOR CARPETS OR THE LIKE.

SPECIFICATION forming part of Letters Patent No. 761,174, dated May 31, 1904.

Application filed August 8, 1903. Serial No. 168,817. (No model.)

To all whom it may concern:

Be it known that I, JOSEPH P. HULL, a citizen of the United States, residing at Easton, in the county of Talbot and State of Delaware, have 5 invented new and useful Improvements in Fasteners for Carpets or the Like, of which the following is a specification.

This invention relates to fasteners for floor, stair, and other coverings, and is particularly 10 adapted for application to stair-carpets and coverings for the latter and includes means whereby the latter carpets and coverings may be quickly secured to steps and risers and readily removed to permit easy detachment or 15 displacement of the carpets or coverings for cleaning or other purposes.

The invention primarily contemplates the provision of an angular body or block having pointed pins or slidable spurs movably disposed in parallel relation in a slot therein and arranged to be projected from diagonally opposite angles of the said slot and actuated by 20 a centrally-applied device whereby the fastener as an entirety when applied will be prevented from turning and becoming irregularly 25 disposed when applied.

A further object of the invention is to produce a simple, effective, and durable fastener for carpets and other covering having in some 30 instances means for securing a rod thereto to serve as an additional or auxiliary fastening means, particularly in relation to stair carpet or covers, the rod construction being specially 35 advantageous in holding crash or other protective coverings on stair-carpets between two of the fasteners and permit the said crash or other covering to be readily applied and removed without disengaging the fastener.

Fasteners of this class have heretofore been 40 used and embodied a metallic plate of angular shape having reduced edges to bear on the carpet or covering and slidable pins or spurs which centrally projected when moved from a seat in the plate and operative by the 45 application of a key applied to the center of the plate between the shanks of the pins or spurs. The central position of the pins or spurs when projected from the plate invariably resulted in a twisting movement of the 50 plate by reason of the fact that one pin or

spur failed to act as a resistance against the other, and hence considerable difficulty ensues in properly applying this old form of fastening. The present improved form of fastener has been devised to overcome the disadvantages just noted. 55

In the drawings, Figure 1 is a perspective view of stairs, showing a carpet or covering applied thereto and the improved fastener thereon with and without the rod attachment. 60 Fig. 2 is a top plan view of the fastener with the cover or shield-plate removed. Fig. 3 is a side elevation of the fastener. Fig. 4 is a transverse vertical section thereof, showing the operating-key applied thereto. Fig. 5 is 65 a top plan view of the fastener with the cover or shield-plate removed, showing a modification in the construction. Fig. 6 is an end elevation of a modified form of the fastener shown by Fig. 5 broken away and showing 70 a portion of a special key used for operating this device.

Similar numerals of reference are employed to indicate corresponding parts in the several views. 75

The numeral 1 designates a body-block, preferably constructed of wood and triangular in form. The apex 2 of the block is curved or rounded to fit snugly against that portion of a stair-carpet at the intersecting angle of 80 each step-board and riser or to press a covering closely against any other angle. This block 1 in both forms of the device is of the same construction, and similar reference-numerals will be used in describing corresponding parts. The outer or base portion of the block 1 is formed with a slot 3, normally covered by a metallic shield-plate 4, securely fastened by screws, as shown. Slidingly mounted in the slot 3 is a pair of reversely-arranged 85 pointed rods or spurs 5, projecting from flat shanks 6, with teeth 7 at their inner opposing edges. The shanks 6 are held spaced apart from each other and are maintained at all times in parallel position by means which will be hereinafter described and differing in the two forms. The pointed extremities 8 of the rods or spurs are movable outwardly from the block at diagonally opposite points or corners 95 of the slot 3 and are shiftable outwardly from 100

and into the block through the medium of a key 9, insertible through a central opening 10 in the shield or cover 4 and either directly or indirectly engaging and actuating the said 5 pointed rods or spurs. When the rods or spurs are projected after the block has been applied, they simultaneously pass through the carpet or covering and enter the wood over which the carpet or covering is placed. By 10 reason of the pointed extremities of the rods or spurs being extended outwardly from the block at diagonally opposite points and to one side of the center and having a simultaneous projection of equal extent the block will be 15 prevented from turning, and thereby expedite the application of the fastener and avoid annoyance incident to the displacement of the block, which would ensue if the pointed rods or spurs were projected from the center of 20 the block or the slot in the latter. One key will be used in applying a number of the fasteners, as the structure of the latter is similar. The blocks can be used alone without any other 25 auxiliary means for securing the carpet or covering in place, particularly on stairs; but in some instances it may be necessary to also use a rod, particularly to hold a crash or other protective covering in place over a stair-carpet between pairs of the fasteners and permit 30 the said crash or other protective covering to be removed and applied at will without detaching the fasteners. For this purpose the block 1 of each fastener at one end close to the apex 2 is formed with a socket 11, the 35 socket ends of oppositely-disposed fasteners being arranged inwardly to removably receive a rod 12. (Shown by Fig. 1.) This rod can be sprung into place by slightly bending the same without detaching either of the fasten- 40 ings with which it engages, or in some instances one of the fasteners may be removed and the other allowed to remain in applied position to arrange the rod against the carpet or covering or to detach said rod.

45 In the form of the device shown by Figs. 2, 3, and 4 guide projections 13 are located centrally in the slot 3 to hold the pointed rods or spurs in parallel relation under all conditions. The teeth 7 at the inner edges of the 50 flat shank 6 are continually engaged by or in mesh with the teeth of the pinion 14, held in the center of the slot, and through the said pinion an angular key-opening 15 extends and coincides with a socket 16 in the block beneath for the reception of a flat head 17 of the key 9, specially arranged for this construction of the fastener. To prevent the shank 6 from being fully projected and fall-

ing out the opposite ends of the slot 3, stop-teeth 18 are formed at opposite terminals 60 of the teeth 7, the said stop-teeth being large enough to obstruct engagement thereof with the pinion 14. In some instances, as shown by Fig. 3, a boss 19 may surround the opening 10 in the shield or cover 4 to brace 65 the key 9 and resist wear by said key around the opening 10.

The form of the device shown by Figs. 5 and 6 also embodies the guide projections 13; but the pinion 14 is lacking in this instance, 70 as well as the stop-teeth 18. The shanks 6 of the pointed rods or spurs have longitudinal slots 20 formed therein and engaged by headed securing devices 21, adapted to strike against the opposite ends of the slots 20 and 75 limit the projection of the pointed rods or spurs. The key 9 in this instance has its working end formed with series of diametrically-opposed ribs 22 and is inserted in a socket 23 in the block 1 in alinement with the opening 10, the latter in this instance being of the same diameter as the socket. The teeth 7 of the shank 6 project over the socket, so that when the ribs 22 are inserted in said socket 80 they engage the teeth and project or retract 85 the pointed pins or spurs when the key is rotated in opposite directions.

The pins or spurs in both forms of the device are projected or retracted by rotating the key for operating the same, and after the fastener has been secured in applied position the key is withdrawn and accidental disengagement of the fastener is avoided. It will also be understood that the proportions of the block may be varied and materials other than wood 95 can be used, if desired. When the block is enlarged or diminished in size, a corresponding change in proportions will be carried out in the remaining parts of the fastener. It is also intended to suitably ornament the face of 100 the fastener as well as the rod coöperating therewith.

Having thus fully described the invention, what is claimed as new is—

The combination of a pair of fasteners, having spurs projectable therefrom and formed with sockets in the inner opposing ends thereof, and a rod detachably held in the said sockets.

In testimony whereof I affix my signature in 110 presence of two witnesses.

JOSEPH P. HULL.
